UNITED STATES PATENT OFFICE

168,547

GAME APPARATUS

Domenick Ippolito, Glendale, Calif.

Application August 16, 1952, Serial No. 21,067

Term of patent 14 years

(Cl. D34—5)

To all whom it may concern:

Be it known that I, Domenick Ippolito, a citizen of the United States, residing at Glendale, in the county of Los Angeles and State of California, have invented a new, original, and ornamental Design for a Game Apparatus, of which the following is a specification, reference being had to the accompanying drawing, forming part thereof.

In the drawing:

Fig. 1 is a perspective view of a game apparatus showing my new design;

Fig. 2 is a top plan view; and

Fig. 3 is a side elevation.

I claim:

The ornamental design for a game apparatus, as shown.

DOMENICK IPPOLITO.
